UNITED STATES PATENT OFFICE.

DANIEL J. O'ROURKE, OF CLARKDALE, ARIZONA, ASSIGNOR TO SULLIVAN MACHINERY COMPANY, A CORPORATION OF MASSACHUSETTS.

TOOL SUPPORT.

Application filed January 7, 1918. Serial No. 210,766.

To all whom it may concern:

Be it known that I, DANIEL J. O'ROURKE, a citizen of the United States, residing at Clarkdale, in the county of Yavapai and State of Arizona, have invented certain new and useful Improvements in Tool Supports, of which the following is a full, clear, and exact specification.

My invention relates to tool supports.

10 It has for its object to provide an improved and simplified tool support which is adapted to permit a wide range of adjustment of the tool in such a manner that the latter is enabled to drive holes disposed at 15 widely different angles. A further object of my invention is to provide an improved, simplified and lightened tool support especially adapted to use in quarries or the like in lieu of the usual cumbersome and expensive gadder frames, in breaking lines in marble or other stone, the same being so adjustable that a hole may be driven at any desired angle. These and other objects of 20 my improvement will, however, hereinafter more fully appear.

In the accompanying drawings, I have shown for purposes of illustration one embodiment which my invention may assume in practice.

30 In these drawings,—

Fig. 1 is a side elevation of my improved support with its tool at work upon a vertical face.

35 Fig. 2 is a side elevation of the same, a portion of the face being shown in section to illustrate certain drilled holes.

Fig. 3 is an enlarged detail vertical sectional view showing the mounting of the swiveled frame.

40 Fig. 4 is a similar transverse sectional view taken on line 4—4 of Fig. 3.

Fig. 5 is a detail view partially in section showing the swiveled mounting of the tool.

45 While the invention may be used with a tool of any desired type, in this illustrative construction I have shown the same as applied to use with a pressure fluid operated hammer drill 1, which is, as usual, provided with suitable feeding mechanism 2, herein of the hand feed type.

In my improved construction, improved means are provided whereby the tool may drill holes at any desired point or angle in either of a plurality of intersecting planes.

50 These means include a suitable base or

mounting, herein shown as preferably comprising a tripod having independently adjustable, preferably weighted, legs 3 adjustable about a horizontally disposed upper pivot member 4, the upper end of the rear leg 3 being bifurcated and disposed on said member 4 between the upper ends of the other legs, as in a usual construction. As shown, a tool carrying bar 5, preferably of

tubular stock, is connected through suitable brackets 6 adjacent its opposite ends, with a plurality of oppositely extending angularly disposed, and preferably tubular, stay rods 7 cooperating therewith to form a truss-like construction and having their inner ends attached at a point in rear and adjacent the middle of the bar 5 to a swivel member or hub 8, which is in turn swiveled within

swivel forming flanges 9 of a suitable sleeve

10. This sleeve 10 is, in turn, carried on the member 4 and adapted to be clamped in a given position thereon by means of an adjustable clamping member 11 which over-

laps one edge of the swivel 8 and is itself

clamped in position on the member 10 by

means of a clamping bolt 12 having a lug

or shoulder portion 13 on its lower end en-

gageable with suitable projections 14 on the member 10 when the nut 15 on the upper

end of the bolt is tightened. Thus, it will

be observed that the bar 5 is mounted in a

swivel mounting in such a manner that, when

the bolt 12 is released, the bar may be ro-

tated in the vertical plane shown in Fig. 1,

about the bearings carried on the tripod. At-

tention is also directed to the fact that by

swiveling the sleeve 10 in suitable bear-

ings 16 formed on the bifurcated upper end

of the leg 3, the bar 5 may also be adjusted

in another vertical plane disposed substan-

tially at right angles to the first plane, the

bar, as shown herein, being freely adjustable

to the right or left of the position shown in

Fig. 1, by simply loosening one or more

nuts 17 which, in a preferred construction,

also serve to clamp the legs of the tripod to

the member 4. It will also be observed that

the drill 1 is herein provided with a suitable

swivel mounting 18 in a supporting bracket

19 carried on the bar 5, the construction

thus being such that in any of the different

positions of adjustment of the bar 5, the

drill 1 may be adjusted angularly relative

to the bar. As shown, the drill is also

adapted to be clamped in its several posi-

tions of adjustment by means of a clamping member 20 in turn clamped in position on the bracket 19 by a clamping bolt and nut connection 21. It will also be observed that to permit of even further flexibility, through the provision of a suitable longitudinally disposed groove 22 in the bar 5, and a cooperating spline 23 carried upon the bracket 19, both this bracket and the drill 1 may be bodily adjusted as desired longitudinally of the bar 5.

As a result of my improved construction, it will be noted that an operator is enabled to drive a hole at any desired angle. For instance, the bar 5, through one of its swivel connections, is adjustable in a vertical plane, and, by reason of its other swivel connection, is also adjustable in another vertical plane disposed substantially at right angles to the first plane; while the drill, due to its own swivel mounting, may be adjusted into any desired angle relative to the bar 5 in a plane parallel to one of these planes, and, due to its slidably bracket, if desired may be adjusted longitudinally of that bar in any position of the latter. Further, it will be observed that through the use of a tripod type of base, the support may be even further adjusted and at the same time adapted to use under widely varying conditions. Attention is also directed to the fact that in my improved construction the support, while possessing great strength and sufficient rigidity to withstand the strains and vibration encountered under service conditions, is at the same time of an exceedingly light type enabling the operator to make the desired adjustments with great facility, all necessity for the provision of such heavy and cumbersome supports as the gadder frames heretofore used, being thus eliminated. It will also be noted that due to my improved construction it is possible to produce a support having the great flexibility of adjustment brought out above, at materially less expense, the construction being of a type which enables the support to be very cheaply and readily manufactured. These and other advantages of my improved construction will, however, be clearly apparent to those skilled in the art.

While I have in this application specifically described one embodiment which my invention may assume in practice, it will be understood that this form of the same is used for purposes of illustration and that the invention may be modified and embodied in various other forms without departing from its spirit or the scope of the appended claims.

What I claim as new and desire to secure by Letters Patent is:

1. In a drilling mechanism, a base, a bar pivotally mounted thereon for pivotal movement about an axis lying between its ends

and disposable vertically adjacent the work, a drill support adjustable longitudinally of said bar, and a drill mounted on said support in a horizontal position and having feeding means associated therewith for feeding the same in a horizontal direction parallel to its axis. 70

2. In a tool support, a base, a bar supported solely thereon and swiveled thereon for adjustment in a plurality of vertical planes, said swivel being disposed adjacent the longitudinal center of said bar, and a tool carried on said bar and disposable with its axis parallel to the axis of said swivel. 75

3. In a tool support, a base, a bar supported solely thereon and swiveled thereon for adjustment in a vertical plane either to a vertical or a horizontal position, and a tool mounted on said bar and adjustable longitudinally thereof to positions parallel 85 to the axis of and at opposite sides of said swivel.

4. In a tool support, a base, a bar supported solely thereon and swiveled thereon for adjustment in a vertical plane either to a vertical or a horizontal position, and a tool mounted on said bar and adjustable longitudinally of said bar to opposite sides of the swivel and also angularly relative thereto in a plane parallel to the axis of 95 said swivel.

5. In a tool support, a base, a bar supported solely thereon and swiveled thereon for adjustment in a plurality of intersecting planes, and a tool swiveled on said bar 100 for adjustment in a plane parallel to one of said planes, the axis about which said bar is swiveled being disposed between the opposite limits of adjustment of said tool on said bar. 105

6. In a tool support, a base, a bar supported solely thereon and swiveled thereon for adjustment in a plurality of intersecting planes, a tool carried on said bar, and means whereby said tool may be bodily adjusted 110 longitudinally of said bar, the axis about which said bar is swiveled being disposed between the opposite limits of adjustment of said tool on said bar.

7. In a tool support, a base, a swinging frame swiveled thereon including a tool carrying bar and cooperating stay rods operatively connected thereto adjacent the opposite ends thereof and together between said bar and its swivel, and a tool carried 120 on said bar. 115

8. In a tool support, a base, a swinging frame swiveled thereon including a tool carrying bar and cooperating stay rods operatively connected thereto adjacent the opposite ends thereof, and a tool slidably carried on said bar and adjustable from end to end thereof and operative to drill a horizontal hole when said bar is vertical. 125

9. In a tool support, a base, a swinging 130

- frame including a tool carrying bar and supporting stay rods therefor, means whereby said frame may be adjusted about said base in a plurality of intersecting vertical planes disposed substantially at right angles to one another, and a tool mounted on said bar in a plane perpendicular thereto and 50 slideable relative to said bar on said bar.
10. In a tool support, a base, a unitary swinging frame comprising a tool carrying bar and supporting stay rods therefor, constituting its sole means of support on said bar, means whereby said frame may be adjusted about said base in a plurality of 55 intersecting vertical planes disposed substantially at right angles to one another, and a tool swiveled on said bar and adjustable in a plane parallel to one of said planes.
15. In a tool support, a tripod, a swinging frame supported solely thereon and including a tool carrying bar and supporting stay rods therefor, means whereby said frame may be adjusted about said tripod in a plurality of intersecting vertical planes disposed substantially at right angles to one another, and a tool swiveled on said bar and adjustable in a plane parallel to one of said planes and longitudinally of said bar.
20. In a tool support, a tripod having adjustable legs, a swinging frame supported solely thereon and including a tool carrying bar and supporting stay rods therefor, means whereby said frame may be adjusted about said tripod in a plurality of intersecting vertical planes disposed substantially at right angles to one another, and a tool swiveled on said bar and adjustable in a plane parallel to one of said planes and longitudinally of said bar.
25. In a tool support, a tripod having adjustable legs, a swinging frame supported solely thereon and including a tool carrying bar and supporting stay rods therefor, means whereby said frame may be adjusted about said tripod in a plurality of intersecting vertical planes disposed substantially at right angles to one another, and a tool swiveled on said bar and adjustable in a plane parallel to one of said planes and longitudinally of said bar.
30. In a tool support, a tripod having adjustable legs, a swinging frame supported solely thereon and including a tool carrying bar and supporting stay rods therefor, means whereby said frame may be adjusted about said tripod in a plurality of intersecting vertical planes disposed substantially at right angles to one another, and a tool swiveled on said bar and adjustable in a plane parallel to one of said planes and longitudinally of said bar.
35. In a tool support, a tripod having adjustable legs, a swinging frame supported solely thereon and including a tool carrying bar and supporting stay rods therefor, means whereby said frame may be adjusted about said tripod in a plurality of intersecting vertical planes disposed substantially at right angles to one another, and a tool swiveled on said bar and adjustable in a plane parallel to one of said planes and longitudinally of said bar.
13. In a tool support, a tripod having adjustable weighted legs, a swinging frame supported solely thereon and including a tool carrying bar and supporting stay rods
- therefor, means whereby said frame may be adjusted about said tripod in a plurality of intersecting vertical planes disposed substantially at right angles to one another, and a tool swiveled on said bar and adjustable in a plane parallel to one of said planes and longitudinally of said bar.
14. In a tool support, a tripod having adjustable legs, a bolt adapted to connect said legs, a member swivelly mounted on said bolt, a frame including a bar mounted on said member, and a tool disposable at an angle to said bar and longitudinally adjustable thereon.
15. In a tool support, a tripod having adjustable legs, a bolt adapted to connect said legs, a member swivelly mounted on said bolt, a frame including a bar swivelly mounted on said member, and a tool disposable at an angle to said bar and longitudinally adjustable thereon.
16. In a tool support, a tripod having adjustable legs, a bolt adapted to connect said legs, a member swivelly mounted on said bolt, a frame including a bar supported on said member, and a tool adjustably swiveled on said bar.
17. In a tool support, a tripod having adjustable legs, a bolt adapted to connect said legs, a member swivelly mounted on said bolt, means mounted on said member for supporting a frame including a bar, and a tool swivelly mounted on a member adjustable along said bar.
18. In a tool support, a standard having adjustable legs, a swivel mounted thereon, supporting stay rods carried by said swivel, a bar carried by said stay rods and adjustable on said swivel in vertical and horizontal planes, a sliding swivel carried on said bar and adjustable longitudinally thereof, and a tool carried on said swivel.

In testimony whereof I affix my signature.

DANIEL J. O'ROURKE.
